Walter A. Knight.

ATTORNEY

UNITED STATES PATENT OFFICE

ARNOLD P. HITZEMAN, OF FORT WAYNE, INDIANA, ASSIGNOR TO WAYNE COMPANY,
OF FORT WAYNE, INDIANA, A CORPORATION OF INDIANA

LIQUID-DISPENSING APPARATUS

Application filed April 23, 1928. Serial No. 272,144.

My invention relates to liquid measuring and dispensing apparatus and particularly to means for keeping the serve valve closed whenever the drain valve is open.

Many types of so called visible dispensing apparatus, such as those used in serving gasoline into automobile tanks, may be so manipulated as to be serving gasoline through the serve valve to customers and at the same time 10 draining back gasoline to the storage tank; both flows being from the elevated transparent container and the flow to storage unknown to the purchaser who supposes his automobile tank is receiving all the gasoline 15 that he sees is flowing from the container.

The principal object of my invention is to prevent such surreptitious withdrawal of liquid to the storage tank.

Another object is to provide such safe- 20 guarding means as will be readily and naturally used by operators of such dispensing apparatus, and those that will be simple and inexpensive to manufacture.

Some States and municipalities require the 25 elevated reservoir to be kept drained until gasoline is pumped into it to supply the next customer's wants, and my improved mechanism readily lends itself to such use.

My invention is illustrated in the accom- 30 panying drawings, in which:—

Figure 1 is a perspective of a visible gasoline measuring and dispensing apparatus with top and bottom broken away and one-half the casing removed to expose the mecha- 35 nism, the drain-back valve being open and the serve valve closed and dogged so that it can not be opened, and

Fig. 2 is a similar view with the drain-back valve closed and the serve valve open.

Referring now to the drawings, 1 is one 40 section of the housing for the pedestal of the apparatus, surmounted by a head 2 upon which tightly seats a glass cylindrical ele- 45 vated container 3 for the gasoline to be dis- pensed, held securely in position between the bottom head 2 and an upper head (not shown) by tie rods 4.

Gasoline is forced into container 3 by pump 5, through fill pipe 6, from a storage tank 50 (not shown). Excess gasoline is drained

from container 3 back to the storage tank through drain pipe 7, and the container may be completely drained through pipe 8 the flow therethrough being controlled by means of valve 9. Weight 10 on the end of lever 55 21 normally keeps drain-back valve 9 closed. Pipe 8 is connected at the bottom into pipe 7.

Gasoline is served from container 3 through serve valve 11, normally kept closed by weight 12 on valve lever 13. Valve lever 13 is se- 60 cured to and rotates with rod 14 which is a prolongation of the valve stem, as is also seg- mental guard 15. This guard is notched at 16 to allow the inner end 20 of a lever 17, hereinafter described, to pass the guard when 65 the inner end of said lever is raised, at which time the guard is retracted and the valve 11 closed.

A lever 17 pivoted to a fork 18 which is clamped to pipe 6 or some other fixed part 70 of the apparatus, has its outer end 19 shaped to form a hook on which to hang the hose nozzle (not shown). The inner end 20 of the lever, when in the raised position shown in Fig. 1, as by the weight of the hose and 75 nozzle, dogs the guard 15 and prevents the opening of the serve valve 11, because the edge of guard 15 strikes against the inner end 20 of lever 17.

To lever 21 is pivoted the lower end of a 80 rod 22, and the upper end of this rod loosely pierces the lever 17, and is held in correct effective length by nuts 23 above the lever and nut 24 below.

It will be seen that when the weight of the 85 hose and nozzle on 19 depresses the outer end of lever 17, the inner end 20 rises if the valve 11 is closed to the position shown in Fig. 1 and prevents the valve 11 from being opened as long as lever remains in that position. The rising of the inner end 20 of lever 90 17 opens drain-back valve 9. If guard 15 is in the position shown in Fig. 2, as it is when the serve valve 11 is open, then the position of the lever 17 can not be changed so that its 95 end 20 will be raised, and so long as the guard stays in that position the drain valve 9 can not be so opened.

Although a preferred form of the invention 100 has been shown and described, it will be un-

derstood that a mechanic, working within the scope of what is claimed, may make changes, without departing from the spirit of my invention.

5 I claim as my invention and desire to secure by Letters Patent of the United States:—

1. In a liquid dispensing apparatus having an elevated container for the liquid to be dispensed, a conduit for completely draining said container back to storage, a normally closed valve controlling the flow of liquid through said conduit and a normally closed serve valve through which liquid is drawn; 10 combined lever actuated means for opening said drain valve when said serve valve is closed, for preventing the opening of the drain valve when the serve valve is open and for preventing the opening of the serve valve 15 when the drain valve is open. 20

2. In combination with a liquid dispensing apparatus having an elevated container for the liquid to be dispensed, a conduit for completely draining said container back to storage, a normally closed valve controlling the flow of liquid through said conduit, a lever for opening said valve, a normally closed serve valve through which liquid is drawn and a lever for opening said serve valve; a guard 25 movable with the serve valve lever, a pivoted lever, a pivot by which said pivoted lever is secured to a fixed part of the apparatus, one end of said pivoted lever projecting outwardly and formed to hang a hose nozzle on, the 30 other end of said pivoted lever projecting inwardly and terminating adjacent said guard to dog the same preventing the opening of the serve valve when the drain valve is open and preventing opening the drain valve when the 35 serve valve is open, and a connecting link between said pivoted lever and the lever of the valve controlling said drain conduit. 40

3. In combination with a liquid dispensing apparatus having an elevated container for the liquid to be dispensed, a conduit for completely draining said container back to storage, a normally closed valve controlling the flow of liquid through said conduit, a lever for opening said valve, a normally closed serve valve through which liquid is drawn 45 and a lever fixed to the valve stem for rotating the same to open said serve valve; a guard fixed to said valve stem, a pivoted lever, a pivot by which said pivoted lever is secured 50 to a fixed part of the apparatus, one end of said pivoted lever projecting outwardly and formed to hang a hose nozzle on, the outer end of said pivoted lever projecting inwardly and terminating adjacent said guard to 55 dog the same preventing the opening of the serve valve when the drain valve is open and preventing opening the drain valve when the serve valve is open, and a connecting link 60 between said pivoted lever and the lever of 65

the drain valve causing said levers to rise and fall together.

In testimony whereof I have hereunto set my hand.
